[57] CLAIM

The ornamental design for a beverage holder, as shown and described.

DESCRIPTION

FIG. 1 is a top right front perspective view of a beverage holder showing our new design. The broken lines are for illustrative purposes only and form no part of the claimed design;

FIG. 2 is a left side elevational view thereof; the right side elevational view being a mirror image;

FIG. 3 is a bottom plan view thereof;

FIG. 4 is a rear elevational view thereof;

FIG. 5 is a top plan view thereof; and,

FIG. 6 is a front elevational view thereof.
